(57) **CLAIM**

The ornamental design for a myofascial massage roller, as shown and described.

DESCRIPTION

FIG. 1 is a first perspective view of a myofascial massage roller showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the myofascial massage roller that form no part of the claimed design. The dot-dashed broken lines in FIGS. 1, 9, and 10 encircling the areas of enlargement form no part of the claimed design.

1 Claim, 10 Drawing Sheets
